(57) **CLAIM**

The ornamental design for a sound machine, as shown and described.

DESCRIPTION

FIG. 1 is a perspective view of a sound machine showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is an enlarged view of a portion indicated with numeric 9 in FIG. 2.

The broken lines in the drawings show portions of the sound machine that form no part of the claimed design.

The dot dash dot broken lines depict the boundaries of the detail areas and form no part of the claimed design.
